UNITED STATES PATENT OFFICE.

GEORGE WILLETT, OF CHICAGO, ILLINOIS.

THREAD-CONTROLLING DEVICE FOR SEWING-MACHINES.

SPECIFICATION forming part of Letters Patent No. 245,905, dated August 16, 1881.

Application filed July 19, 1880. (Model.)

To all whom it may concern:

Be it known that I, GEORGE WILLETT, of Chicago, in the county of Cook, and in the State of Illinois, have invented certain new and useful 5 Improvements in Thread-Controlling Devices for Sewing-Machines; and I do hereby declare that the following is a full, clear, and exact description thereof, reference being had to the accompanying drawings, making a part of this 10 specification, in which—

Figures 1 and 2 are side elevations of the head of the stationary arm of a sewing-machine having attached thereto my thread-controlling mechanism, and show, respectively, 15 the positions of parts when the needle-bar is at the highest and at the lowest limit of its motion. Figs. 3 and 4 are vertical central sections of said thread-controlling mechanism upon lines parallel with said stationary arm, 20 and show, respectively, the relative positions of parts shown in Figs. 1 and 2. Fig. 5 is a central longitudinal section of the plunger-tube separated from its connecting parts. Fig. 6 is a perspective view of the lower end of the 25 head from the rear, and shows the separable cap. Fig. 7 is a central longitudinal section of the plunger and its guide when arranged as a positive take-up. Fig. 8 is a rear elevation of the presser-bar, needle-bar, and tube for regulating the tension of the thread with relation 30 to the thickness of the fabric being operated upon in the upward movement of the needle-bar, the full lines showing the highest position of said tube and the dotted lines its lowest position. Fig. 9 is a like view of the same, the 35 vertical position of the regulating-tube being adjusted by a hand-lever, and Fig. 10 is a side elevation of said parts.

Letters of like name and kind refer to like 40 parts in each of the figures.

The design of my invention is to enable the thread to be drawn from the spool in proportion to the thickness of the goods under the presser-foot, thereby making the tension on the 45 thread the same on thick or thin goods; and to this end it consists, principally, in the means employed for automatically varying the quantity of thread drawn from the spool in accordance with the vertical position of the presser-foot, thereby adapting the tension of the thread 50 to the thickness of the goods being operated

upon, substantially as and for the purpose hereinafter specified.

It consists, further, in a thread loop or guide connected with the needle-bar by means of an 55 adjustable spring, and adapted to draw the thread over a relatively-fixed bearing as said needle-bar rises, substantially as and for the purpose hereinafter shown.

It consists, further, in the construction of 60 the take-up, whereby the same may be made compensating or positive, as desired, substantially as and for the purpose hereinafter set forth.

It consists, further, in the means employed 65 for operating the thread-controlling device, substantially as and for the purpose hereinafter shown and described.

It consists, finally, in the combination of the 70 thread-controlling and take-up mechanism, substantially as and for the purpose hereinafter specified.

In the annexed drawings, A represents the head or housing of the stationary arm B of a sewing-machine, within which head are contained a needle-bar, C, and a presser-bar, D, of usual construction. The head A in rear of the needle-bar C is cut away, except near its upper and lower ends, and within the latter is provided a round vertical opening, a, that receives and contains a tube, E, which is preferably constructed from wire wound spirally, and has its lower end projecting below said head. The upper end of the tube E is loosely connected with one end of a bar, F, which extends horizontally across the head A, is pivoted at or near its longitudinal center to or upon said head, and has its opposite end connected with the presser-bar D, the arrangement being such as to cause said tube to be raised 85 by the downward movement of said presser-bar, and to be moved downward as the latter is raised. For convenience in placing said parts in and removing the same from position, the rear side, at the lower end of said head A, 90 is made separate like a cap, and is secured in place by means of a screw.

Secured upon and extending rearward from the central portion of the needle-bar C is an arm, C', which is provided with a vertical 100 threaded opening, c', that coincides with the opening a and receives an exteriorly-threaded

tube, G, which has a length of about one and one-half inch. The tube G has an axial opening, g, which, from its lower end to or near the longitudinal center of said tube, has a diameter of about one-sixteenth of an inch, while from thence to the upper end of said tube said opening has a considerably larger diameter.

Within the tube G is fitted a rod, H, that loosely fills the lower portion of the opening g, and is provided near its lower end with a collar, h, and has its upper portion threaded and provided with a nut, h'. Around the upper portion of said rod, between said nut h' and the bottom of the enlarged portion of the opening g, is placed a spiral spring, I, which operates to hold said rod H at the upper limit of its motion with a yielding pressure, that may be increased or diminished by turning said nut h' downward or upward upon said rod. The lower end of the rod H is provided with a thread-eye, h², which is arranged for the passage of thread from the rear toward the front of the machine, and in order that said eye may maintain such position said rod is provided with a radial lug, h³, which fits loosely into a vertical slot, g', that is formed within one side of the tube G, said arrangement insuring the circumferential position of said rod without interfering with its free vertical movement within said tube.

A thread-eye, K, secured to the lower end of the head A in rear of the tube E, a second thread-eye, L, secured to and projecting rearward from the rear side at the upper end of said head, and an eye, c, secured to and projecting rearward from the lower end of the needle-bar C, completes my improvement, the operation of which is as follows, viz: The thread M, after leaving the tension, is passed downward through the eye L, forward through the eyes K and h², and thence downward through the eye c to the needle. As the needle-bar C descends the rod or plunger H moves simultaneously downward, its thread-eye h² at the lower limit of such motion being upon a line with the thread-eye K. When the needle-bar C ascends the thread M is drawn by the rod or plunger H upward within the tube E, such movement of said thread being continued until its tension is greater than the force of the spring I, when said spring will yield and permit the arm C' to continue its upward motion without further movement of said thread. The thread M, passing from the eye K to the eye h², and from the latter to the eye c, is drawn across the lower end of the tube E at an angle which is lessened as said tube is raised and increased as said tube is lowered, and as the length of thread required to extend between said points increases in proportion to the departure from straight lines, it will be seen that when said tube is lowered an increase in the amount of thread drawn from the spool will result, while by raising said tube the opposite will be true.

As the vertical position of the tube E gov-

erns the amount of thread drawn from the spool, and as the amount required is greater for thick goods than when thin goods are being operated upon, it will be seen that the connection of said tube with the presser-bar accomplishes the desired result, the elevation of said bar by placing beneath the foot thick goods causing said tube to be automatically lowered, so as to increase the amount of thread drawn from the spool, while the lowering of the presser-bar, as lighter goods are operated upon, causes said tube to rise and lessens the amount of thread drawn from the spool, thereby causing a perfectly uniform tension upon the thread at all times, whether thick or thin goods are being operated upon.

In order that the tube E may be adjusted vertically, when desired, without reference to the movements of the presser-foot, I journal a toothed pinion, f, within a suitable recess in the head A, adjacent to and in position to engage with the grooved periphery of said tube, and to the rearward projecting pivotal bearing or journal of said pinion I attach a lever, f', by means of which said pinion may be rotated, a downward movement of the outer end of said lever causing said tube to be raised, while by raising the outer end of said lever said tube will be lowered. When thus adjusted vertically the position of the tube E may be insured by providing a toothed segment for engagement with the outer end of the lever f', or a pin may be passed through an opening in the end of the latter and have its inner end contained within one of a number of openings provided within the rear side of the head A. If, now, the upper end of the tube E is disconnected from the bar F, said tube will be left free to be moved by the pinion f and lever f', and when adjusted will remain in position. When said tube E is connected with said bar F the vertical movements of the former will cause said lever f' to change position, as shown by the dotted and full lines of Fig. 7.

By means of the nut h' the resistance offered by the spring I to the downward movement of the plunger H may be increased or diminished.

The screw-thread upon the exterior of the tube G enables the same to be easily adjusted to the necessary vertical position.

If it is desired to make the movement of the take-up positive, the nut h' is screwed downward until the collar h is drawn firmly against the lower end of the tube G, in which position there is no yielding in the upward pull of the take-up. When the take-up is thus used it is best to remove the spring I from within the tube G.

Having thus fully set forth the nature and merits of my invention, what I claim as new is—

1. As a means for controlling the amount of thread drawn from the spool, the tube E, arranged between the take-up device G H h² and the lower end of the needle-bar C, and connected with the presser-bar D by means of the

pivoted bar F, and adapted to be automatically raised or lowered as said presser-bar is lowered or raised, said parts being combined in the manner and for the purpose specified.

5 2. The combination, with the needle-bar C and the bearing or tube E, fixed relatively to said needle-bar, of the plunger H, having the thread-guide h² and means for yieldingly connecting said plunger with the needle-bar, substantially as and for the purpose shown.

10 3. The hereinbefore-described take-up, consisting of the tube G, fitted within and moving with the arm C', and provided with the axial opening g, the plunger H, fitted within 15 said opening and provided with the collar h, nut h', and thread-eye h², and the spring I, placed within said tube around said plunger, said parts being combined with each other, the needle-bar C, and with a stationary thread-eye, 20 K, substantially as and for the purpose set forth.

4. In combination with the tube E and its housing A a, the pinion f and lever f', substantially as and for the purpose shown and described.

25 5. In combination with the tube E, the pivoted bar F, the head A, and the presser-bar D, substantially as and for the purpose specified.

6. The combination of the vertically-adjustable tube E², the spring-plunger H, the needle-bar C, and intermediate mechanism connecting said parts with each other and with the head A, substantially as and for the purpose shown.

In testimony that I claim the foregoing I have hereunto set my hand this 6th day of July, 35 1880.

GEORGE WILLETT.
